UNITED STATES PATENT OFFICE.

ISAAC S. KEELER, OF GRAND RAPIDS, MICHIGAN.

VENTILATOR DEVICE.

1,174,255.

Specification of Letters Patent.

Patented Mar. 7, 1916.

Application filed February 23, 1915. Serial No. 9,959.

To all whom it may concern:

Be it known that I, ISAAC S. KEELER, a citizen of the United States of America, residing at Grand Rapids, in the county of

5 Kent and State of Michigan, have invented certain new and useful Improvements in Ventilator Devices; and I do hereby declare the following to be a full, clear, and exact description of the invention, such as will enable others skilled in the art to which it ap-

10 pertains to make and use the same.

This invention relates to a ventilator construction adapted to be used to hold a door partially open. This construction may be 15 used in several relations but is especially adapted to be used in motor vehicles to hold the doors usually closing the front and rear compartments of the vehicle open a short distance, thereby permitting a circulation of 20 air through the compartment.

It is the object and purpose of the invention to provide a device of this character which shall contain several new and useful features of construction and operation 25 whereby a door may be rigidly held in partially open position and insurance had against noise and rattling ordinarily occurring from the continual vibration to which a vehicle of this kind is subjected.

30 The construction by which these ends are attained is shown in the accompanying drawings, in which:

Figure 1 is an elevation, with the door shown in section, illustrating the ventilator device. Fig. 2 is a plan view of the construction shown in Fig. 1. Figs. 3 and 4 are sectional views taken on the line $x-x$ of Fig. 5 showing, respectively, the positions of the spring in the socket member when in- 35 operative and when in use. Fig. 5 is a front elevation of the socket member attached to the door; and Fig. 6 is a section on the line 40 6-6 of Fig. 1.

Like reference characters refer to like 45 parts throughout the several views of the drawings.

In the embodiment shown the back of a seat is indicated at 1 and the door at 2, it being understood that the door is hingedly 50 mounted so that its front edge may move back and forth with relation to the back 1. A base 3 of any suitable material is rigidly connected to the back 1 and carries a mem- 55 ber 4 pivotally mounted thereon. The construction by which this pivotal mount is made comprises a screw having an enlarged

head 5, the shank 6 being threaded into the base 3 with the head positioned a distance above the base or substantially in the same plane with the outer surface of the member 60 4. Member 4 is bored forming a cup adapted to receive the head 5 and a strong coil spring 7 is interposed between the head and the lower or base portion of the cup. It will be evident that with the spring 7 under compression member 4 is continuously pressed against base 3, and the spring insures against any rattling or lost motion of any character taking place between parts 3 and 4.

Member 4 extends outwardly a distance 70 from the base 3 and at its free end is provided with spaced apart ears 8 between which arm 9 is pivotally mounted on the pin 10 which is positioned substantially at right angles to the axis of the screw 6. At its 75 outer end arm 9 is enlarged forming a head 11.

On the inner face of the door 2 a socket member 12 is positioned and rigidly secured by means of the screws 13. The socket 80 member is formed with a raised portion 14 slotted vertically as indicated at 15 and having a substantially circular opening 16 at the upper end of the slot large enough to receive the head 11 while the slot is of sufficient width to receive the arm 9 but will not permit the passage of the head. A leaf spring 17 is secured in place between socket member 12 and the door 2, the upper screw 13 passing through the spring and the lower 90 end of the spring is bent away from the door as indicated in Fig. 3 normally lying adjacent the opening provided by the slot 15. In the use of this construction door 2 is opened a short distance, head 11 passed through opening 16 and forced downwardly into the socket member pressing against the end of spring 17 as indicated in Fig. 4. By reason of the pivotal connection of member 4 to the base 3 on a horizontal axis and of 100 the arm 9 on an axis at right angles to the axis of screw 6 a substantially universal joint is provided permitting the location of the head 10 in a great number of positions and its engagement with and disengagement 105 from the socket member is readily accomplished. When engaged in the socket member the pressure of spring 17 to the head 11 forces the head into contact with the inner side of the raised portion 14 guarding 110 against rattling that would otherwise occur in the operation of the motor vehicle, and

holding the door open a short space to permit the entrance and circulation of air through the compartment. This construction including a plurality of joints renders it useful in a great number of positions. The shape of head 11 precludes any catching with the clothing of the occupant of the motor vehicle as in the hooks used heretofore. The construction of the pivotal joint 10 where the member 4 is attached to the base 3 insures against rattling, at the same time permitting the ready movement of the member 4 with respect to the base 3 while the engagement of spring 17 with the head of arm 9 insures against rattling and other undue noise when the device is in operation. Springs 7 and 17 in effect absorb the vibration occurring from operation of the motor vehicle and render the device practically noiseless when in use. Devices of this character are applicable to doors of any type whether hinged to swing from a forward pivot or one at the rear in a motor vehicle. And furthermore, all of these advantages 20 resulting from my construction are attained by a very simple mechanism easily manufactured and assembled at a comparatively low cost.

I claim:

30 1. In a device of the character described,

a base adapted to be connected to a suitable support, a member provided with a cup at one end, a pivot member having an enlarged head passing through the cup and secured to the base, a spring located between the head 35 and bottom of the cup and an arm pivotally connected to the member by a pin, the axis of which is disposed at an angle to the axis of the said pivot member.

2. In combination, a support, a base secured thereto, a member pivotally connected to the base to turn about an axis normal to the base, an arm having an enlarged head at its free end pivotally connected to the member to turn about an axis positioned substantially at right angles to the pivotal axis of the member, a door, a socket member secured to the door having an upper opening adapted to permit the passage of the head on said arm, and a leaf spring secured at 50 one end between an end of the socket member and the door, the other end thereof extending forwardly to bear against said head, substantially as described.

In testimony whereof I affix my signature 55 in presence of two witnesses.

ISAAC S. KEELER.
